APPARATUS FOR THE PACKAGING OF MILK

Claude E. Pope, Oakland, Calif.

Application April 3, 1939, Serial No. 265,806

58 Claims. (Cl. 93—39.1)

This invention relates to the art of packaging liquid milk, that is, the so-called fresh, raw or pasteurized, milk, and is more particularly concerned with mechanism for packaging such milk in paper containers and by such means that, in the result, the total cost or economic effort incident to milk distribution, as compared to prior methods in general, is substantially diminished.

The mechanism for forming paper containers for the reception and distribution of milk in standard size, or quart, pint, or the like, is preferably of such character that the machines can give final form to the containers at the filling plant for the reasons that; among other things, a great number of containers may be transported to and stored at the filling plant in a comparatively small carrier and storage space when the parts of the container are in folded or collapsed state during such transport and storage; the containers must normally be given treatment to insure their sterility immediately prior to filling with the milk to be filled at any event and so are best and most economically both assembled to expanded or container form and sterilized prior to filling with the milk to be contained thereby; and the attendant responsible for the filling and capping machine can also attend to the container assembling and sterilizing mechanism with the incident economy in personnel charges against the ultimate product.

It is one of the principal objects of this invention to attain the above recited objectives through the employment of the principles herein-after set forth.

Various types of paper containers have been proposed for the packaging of fresh milk some of which have proven eminently successful both from a mechanical and from an economic aspect. Other types, while mechanically preferable to the more successful, fail because of their uneconomical aspects.

Applicant employs a type of container which is of the general shape of the latter type, that is, to have better mechanical properties than the types now in use, and which is capable of low cost manufacture comparable to those of such successful types.

Accordingly this invention is further concerned with means for fabricating containers of this character at low cost and to have best possible mechanical characteristics.

In order to achieve improved economy here, as in other highly developed arts, it becomes necessary to employ methods and means which are self controlled, that is, of the automatic variety,

and preferably that few manual operations be required.

It is, accordingly, another object of this invention to provide for substantially fully automatic machinery for the fabrication, sterilization, and transport to automatic filling and capping apparatus for container of the character above alluded to in uniform and continuous sequence, whereby, while the milk is being pasteurized, the container is being constructed and the milk and container concurrently approach the filling machine, each having been fully processed for association with the other, and whereby, during their processing, they have been in the same plant, under the control of the same operator.

Other and specific objects of the invention will be in part apparent and in part specifically referred to in the following description and in the accompanying drawings wherein are shown preferred and modified mechanisms for achieving the various objects and in connection with which the methods hereof are rendered effective.

In the drawings:

Figure I is a fragmentary perspective view of the fabricating machine, this view being presented chiefly for the purpose of illustrating relative positions of the various mechanisms.

Figures II to IVa illustrate, in fragmentary form, the construction and operation of the mechanism for feeding and expanding the container body.

Figure V is a fragmentary plan of the fabricating machine, certain parts and mechanisms being removed to expose others.

Figure VI is a fragmentary plan view of the bottom feeding and assembling mechanism.

Figures VII to IX illustrate, in fragmentary way, the mechanism for bringing the body and bottom portions of the container together.

Figures X and XI show details of mechanism for translating the body from processing position to processing position in relation to each other.

Figure XII is an elevation of a modified sectionalized breaker head.

Figure XIIa is an elevation of the preferred structure for breaking the tabs of the end wall.

Figure XIII is a section on the line 13—13 of Figure VII.

Figure XIV is a sectional elevation through the heat and pressure processing mechanism.

Figures XV to XVIII illustrate the construction of the integrating heads for applying pressure and heat when positioned as at 434 in Figure XIV.

Figures XIX and XX are fragmentary views in perspective and plan to illustrate the mechanism for discharging the fabricated container and for delivering the same to the sterilizing and waxing machine.

Figures XXI to XXV illustrate by sectional elevation, fragmentary plan, and three fragmentary views, the construction and operation of the sterilizing and waxing machine.

Figures XXVI to XXVIII show the various parts of the container as referred to in the specification and the latter illustrates the body blank as received by the machine.

Figure XXIX is a sectional detail on the line 29—29 of Figure XI.

Figures XXX to XXXVI illustrate by side, end, and fragmentary views the preferred construction of a body feed.

The container of this invention is partially fabricated from two portions illustrated in Figures XXVI and XXVII. The body portion 2 is received in collapsed condition and is of such form, illustrated in end view in Figure XXVIII, as to be expandable to a four sidewall closure of frustro-pyramidal configuration. This body portion 2 is preformed from a flat stiff sheet, scored or weakened along four lines 4 on one side of the blank and is provided with a lap portion 6 along one score line which is subsequently glued to the inside edge surface area 8 of the remote side wall portion 10.

A property retained in the material of the body portion after formation thereof is employed in the subsequent handling of the blank by the fabricating or assembling machine and, accordingly, it is desirable to point out that, as shown in Figure VII, the two inner sidewall forming portions 18 and 20 remain in the same plane, that is without bending the material along their common scoreline 12. The remote sidewall portions 10 and 11 are folded along the scorelines 14 and 16 and flattened against the respectively adjacent inner side wall forming portions 18 and 20 so that the lap portion 6 lies interiorly of sidewall 10. The material along scoreline 22 is retained without bending. The lap being bonded along the flap and area 8, it will be appreciated that the body has a certain resistance to expansion insured by the as yet unbent material along the scorelines 12 and 22. This tendency to resist expansion is employed to advantage as will hereinafter be pointed out.

It will be observed from Figure XXVI that the edges 24 form angles less than ninety degrees with the scorelines and it will be appreciated that there is only one relative position of these edges in which they are all in the same plane and that is when the edges lie in the same plane at right angles to each other. In this latter condition the lower edges form a uniplanar bottom which insures a container which can be set on any flat surface and expected to remain there in stable equilibrium.

By securing the edges in the same plane the true form of a frustro-pyramidal shell is insured with its accompanying strength and rigidity.

The second portion of the open container consists in the flat stiff paper blank 26 having a generally square conformation 28 which forms the bottom area exposed to the interior of the container in final form and four lateral tabs 30 each comprising a portion 32 the end edges of which diverge at an angle corresponding to the angles 34 of body 2, such end edges terminating at the end of the scoreline 36. The second portion 37

of the tabs 30 converges from the terminus of the scoreline 36 at a similar angle. A scoreline 38 is provided between portions 28 and 32.

As will be observed in Figure VII, the portions 32 are bonded to the areas along the lower edges of the sidewalls and interiorly thereof with the end edges of the portions 32 lying snugly in the corners formed by the scorelines 14, 16, 22, and 12, there being sufficient abutment to form a seal of substantial strength. The portions 31 are lapped on the outside of the edges of the side walls in juxtaposition to the portions 32. Accordingly the tabs 30 embrace the lower edges of the side walls and, being bonded thereto, form a rigidizing brace therefore capable of supporting the entire container and its contents on the rectangular hollow wall section below the bottom portion 20, this latter being therefore relieved from exposure to puncturing and wear. This relieved bottom also permits ease of handling the container in various ways incident to its processing and the area subject to frictional contact is minimized.

The body portion and the bottom portion are assembled into a rigid open-topped container of frustro-pyramidal shell conformation from their flat conditions, as illustrated in Figure XXVIII by a series of steps performed in various sequential positions in a machine which receives these elements respectively in piled and or columnar relationship and transports them from such relationship for processing in step by step manner.

The body portions 2 are fed through a hopper from which they are released individually to a traveling expanding mechanism which transports and incident thereto expands this portion so that it is placed in a bottom inserting position where it is received and held by a second transporting mechanism. The bottom portions are fed from their hopper and transported to a gluing position where a bottom applying mechanism applies glue to the bottom tabs and applies the bottom to the body portion.

The body and bottom portions are henceforth transported as a unit by the second transporting mechanism to a position where the bottom tab portions 31 are folded or broken along the scoreline 36 to an angle such that they extend reversely along portions 32 but do not necessarily contact the sidewall to which they will subsequently be bonded.

From the foregoing position the unit is translated to a moving integrating device which receives the unit and applies pressure and heat to the portions to be bonded to rigidly seal the portions together, applying the heat and pressure for a fixed time interval and at the end of this time discharging the unit for reception by further translating means and for subsequent sterilization and application of a wax coating as will be described in due course.

The various mechanisms are described in connection with the drawings in their proper order below:

Body hopper, body feeding, and expanding mechanism

In Figures I to V there is shown a mechanism for removing a body blank 2 from a vertical hopper 100 having vertically disposed guideways 102 and bottom shoulders 104 and 106 for supporting a stack of body blanks in the guideways. Shoulders 104 underlie the side of the blank at a, b, Figure V, and the supporting

portion thereof is slotted as at 108 to permit movement of the blank to the left as viewed in Figure II so that the narrower portion of the blank drops through the space between shoulders 104 from a position vertically above the dotted outline of the blank as shown at c.

The shoulder 106 underlies the narrower end of the blank stack and extends thereunder a short distance through which it is preferably sloped downward. Carried in a suitable guideway in shoulder 106 is a plunger 110 having a blank engaging shoulder 112 of such height as to engage and move only one body blank for each reciprocation thereof to the left as shown in Figure II. Plunger 110 is reciprocated in timed relation to other mechanisms by means of an oscillating crank arm 114 suitably connected as by a pitman to a second crank on the oscillated shaft 116 which latter shaft is oscillated from main drive shaft 118 (Figure I) by a suitable pitman 120 connected to said shaft by a crank 122.

After its release from the hopper the body 2 falls into the cradle forming arms 124, Figures I to V for carriage and expansion into the dotted line position d of Figure II. Cradle arms 124 are pivotally and adjustably secured on the projecting end 126 of shaft 128 by a screw 130, the members 124 being there possessed of the property of adjustment to the angularity of the blank edges as indicated in Figure V and being rotatable from the position of Figure III to that of Figure IV about the axis of shaft 128.

Shaft 128 is carried in a bearing 132 which is slidably carried by a sliding bracket 134 secured to a slide member 136 which is slidably but non-rotatably mounted on oscillating arm 138, whereby the positions of the cradle members 124 may be juxtaposed and adjusted for bodies 2 of different lengths and side angularities. Arms 138 are secured to shaft 116 for oscillation therewith between positions e and f as indicated in Figure II, such oscillation being effected from a pitman 120 as heretofore described.

The cradle members 124 are caused to assume angular positions about the axis of shaft 128 corresponding to the positions indicated in Figures III and IV so as to present open arms for reception of the blank 2 in the first position and to thereafter immediately firmly grip the blank and to partially expand it to a position somewhat as indicated in Figure IV. To effect movement of the cradle members 124 between these positions there is rigidly secured to the shaft 128 a cam arm 140 extending into the path of a control member or plunger 142 slidably carried in eye members 144 and provided with an enlarged head 146 for engagement and release from the stationary control stop or frame members 148, springs 150 secured to the arms 140 and the sliders 136 serving to bias the arms to the body expanding position and to hold them in this position except when plunger head 146 engages against the stops 148.

The oscillating arms 138 not only rotate about the axis of the shaft 116 but also oscillate about pivot pin axis 152, Figures II and V, being biased to a position at right angles thereto by flat springs 154 secured to the pivotal bell crank 156 and extending therefrom to bear upon the flat surface of the square shaft as shown in Figure II.

During the oscillation of the arms 138 the tips 158 thereof are caused to follow a cam path by means of cam bars 160 of arcuate conformation with respect to the axis of the shaft 116 75

and of generally inward and downward convergence with respect to each other as shown in Figures II and V. The tips 158 of the oscillating arms 138 travel on the outside or remote sides of the cam members 160 in proceeding toward the horizontal position e of Figure II and, just prior to the upper terminus of the cam member 160, the plunger head 146 abuts the underside of stop 148 and is arrested so that the Y shaped cradle members 124 move to the open arm position shown in Figure III. Then tips 158 clear the end of cam 160 stationary leaf springs 162 force tips 158 inwardly toward each other thus carrying heads 146 out of abutting relation with stops 148 whereupon springs 150 rotate the cradle members to the position of Figure IV in which it will be noted that the bottoms of the troughs thereof have approached each other and caused the initial expansion of the body blank as shown.

It will be appreciated from a consideration of the discussion of the body blank itself, that the tendency thereof to resist expansion is now operative to cause the same to firmly expand into the arms of the cradle means in a manner to prevent dropping therefrom as well as to prevent longitudinal shifting with respect thereto.

The direction of rotation of the shaft 116 is reversed as the tips 158 clear the end of the cam 160 and the release of body 2 is caused to occur in time enough to permit it to drop onto arms 124 whereupon it is immediately given the collapsing action and a translation in the direction of the position d of Figure II.

35 The tip 158 of arms 138 being now on the inside of cam 160 and moving downwardly, the convergence of the cams causes the cradle members to approach each other to fully expand the body and to slightly collapse it to the diamond form as illustrated in Figure IVa whereby the body tends to expand itself into the square section indicated in dotted lines in Figure IVa, for a purpose to be explained. This over-expanded condition is maintained into the position d of Figure II corresponding to which the tips 158 of arms 138 are released for divergent movement under the influence of flat springs 154. Such release of the arms 138 carries the cradle members 124 away from each other and from the body to a position as illustrated by dotted lines in Figure IVa, the body having been released to take the position d in the cradle of a carrier later to be described more in detail but which may now be referred to as elements 326, 328, 600, and 636 of Figures XI and X respectively.

60 The arms 138, having released the body as indicated and having cleared its cradles thereof, their movement is again reversed by shaft 116 and the tips now travel on the outside of cam 160 to the position e again for the reception of another body blank and a repetition of the cycle of its activity.

The opening of the blank 2 may be certainly initiated by a separator wedge 164 placed in the path of movement of the blank under action of picker 110 so as to split the large end of the blank slightly as it enters the position c thus insuring a spreading thereof. The wedge 164 is pivotally mounted on a shaft 166 spring biased to the full line position of Figure II so that the same may follow the blank edge and create a slight drag. Such initiating means is not necessary where the body blanks are received in perfectly folded condition.

It is preferable to insure that the edges of the

blanks lie in the same plane by means of a forming weight 168 having bearing portions 170 to engage the top of the blank stack opposite the shoulders 104 and 106. A passage is provided in the rear bearing portion to clear picker 110.

The frame 148 is carried on columns 172 supported by a stationary plate 174 on the main body of the machine, as shown in Figure I, and to the lower ends of the inner columns are adjustably secured the lower ends of the cams 160 as by clamps 178.

The hopper 100 may vary in length toward the left in Figure II so that blanks 2 of varying height may be accommodated and the sliders 136 are therefore adjustable along arms 138. The guideways 102 are suitably secured together and rest in frame 148 on an angle piece, whereby the same may be shifted to the right or left to accommodate body blanks of different lengths, the open ends of the blanks being of the same cross section. A different conformer 168 is necessary for each size blank operated upon.

The adjustment at 130 is varied for different size blanks, as is that at 176. A buffer spring is provided at 180 to prevent overtravel of the tips 158 on release at position e, Figure II.

The bottom end of a shorter blank would take a position h in Figure II, the opposite end coinciding with that of the larger blank.

In Figures XXX to XXXVI an alternative mechanism to serve as a hopper, feeder and expander to place the expanded body in the position d is shown to comprise a horizontally disposed trough member formed by sidewall members 101 secured to plate 174 to form a trough hopper of trapezoidal section corresponding to the flattened contour of the body blank.

Reciprocatively mounted in guide slots 103 in the side walls of the slot is a feeder plate 165 disposed within the trough and having tongues 107 passing through said slots rigidly secured to arms 109 forming part of sliders 111 sliding on the longitudinal rods 113 and biased toward the position d by a weight W carried by a cable 115 trained over suitable sheaves 117.

Feeder plate 105 bears against the rearmost of a batch of body blanks 2 which are fed toward the right thereby and through the discharge end under control of a unit discharge mechanism comprising a set of similar gate devices 119. Each gate comprises an oscillatory head formed by axially aligned plates 121 and 123 joined by an integral circular section 125 whereby to form an annular groove between said plates of a thickness or section sufficient to receive the edge of one only of the collapsed body blank 2.

Plate 121 is generally circular, is disposed away from the observer of Figure XXXI, and is cut away along a chord tangent to the section 125. Plate 123 is generally segmental and is juxtaposed to the cutaway portion of plate 121 and extends a substantial distance in overlapping relation with plate 121 as at 129. Shafts 127 are rotatively mounted in trunnions 131 and are given an oscillatory movement from an oscillating shaft 133 driven from shaft 118 and acting through pitman 135.

As shown in Figure XXXI, plates 119 lie in the path of the gravity fed body blanks. The rim of the plate 119 is knife-edged to permit the same to enter between the first and second body blank. In the position shown, the blank cannot move beyond the plate 121. By a downward pull on the pitman 135, the chords 131 are brought into coincidence with the inner edge of the

sidewalls 101 of the trough whereupon the first blank is forced forwardly and is stopped by the juxtaposed portion of the plate 123. Rotation has now stopped and the portion 141 of the plate 121 is opposite the dividing plane between the first and second blank. Upon reversal of the rotation, portion 141 enters between the first and second member in this plane whereby to separate them slightly and to block the path of the second blank. At this stage the overlapping portion 139 insures the exact positioning of the two body members for insertion of the knife edge of the member 121 until it has entered a substantial distance.

The reversed rotation continues to the position shown in Figure XXXI during which a cam member 143, mounted on the member 121 in trailing relation to the releasing and overlapping portion 139 of member 123, forces the body blank forwardly clear of the forward extent of the member 123.

As the blank is released it drops into the waiting arms of a cradle mechanism which translates, expands and deposits the expanded body member to the position d for release to other mechanism later described. Cradle members 145 comprise a right angularly sectioned elongated V member one of the legs 149 of which is very short as shown to permit entry of the blank edge. Cradle member 145 is pivoted as at 151 for lost motion with respect thereto between adjustable stops 153 in response to gravity and to conform to the enveloped edges of the body blank. The stops are so adjusted that the upper ends of the V members are gravitally biased inwardly and to engage the edge of the body blank at or substantially at the same time that the lower end engages the blank.

The pivot 151 is so located that after a certain amount of rotation of the leg 155 inwardly, the line of action becomes such as to cause the member 145 to move upwardly against the upper stop wherein the desired degree of overexpansion is attained for the overexpanded body blank. The pivot 151 and stops 153 are carried upon one leg 155 of a crank the other leg 157 of which forms a cam follower for a stationary closed-path cam 159. The crank is bodily carried by the longitudinally reciprocative slide member 161 driven by shaft 133 by linkages 163 and 165 from a position to receive the blank as it is released by gates 119 to a position for release to the position d. The cam 159 is so constructed and arranged that the cradle arms approach the release position of the blank from a position laterally of the gates 119, being released from such lateral position to drop directly inwardly in embracing relation with the edges of the blank as the same is released from the gate. A portion of the legs 149 adjacent the lower end thereof and between the ends of said legs is cut away so as to clear the cam ejector on plate 121 and the timing is such that the lower end of legs 149 comes in just behind the said ejector cam and just preceding the time of final release from the groove by the head 123. By this construction there is no time when the blank is not positively positioned incident to the transfer from the magazine.

After receipt of the blank by the cradle arms they are moved in the direction of position d and the cam 159 functions to cause the arms to approach each other the freedom between stops 153 being of such extent that the blank edges lie in the groove continuously. The blank is overexpanded during this movement for reasons

heretofore explained in connection with the first modification described. As soon as the position *d* is reached the cam 159 functions to release the blank and the arm 157 follows cam 159 by such a return path therein that the arms 145 remain retracted until again in enveloping relation to the releasing position of the succeeding blank from the gates 119.

Bottom blank: Hopper, feed, glue applicator, and bottom inserting mechanism

The bottom is applied to the body portion while it makes a short vertical excursion vertically along its own axis from the position of Figure II, and, therefore, the progress of the bottom blank, which occurs while the body blank travels from *c* to *d*, will now be set forth.

The hopper 180, Figures II, V, VI and VII, is carried upon the vertically adjustable horizontal plate frame member 182 and secured thereto by suitable columns 184. The bottom blanks are stacked between vertical guides 186 in juxtaposition to the hopper release chamber 188 formed in the members 190 having guide slots 192 therein for receiving the opposite edges of the bottom blanks and guiding them to a position *j*, Figure VII, overlying the glue applicators and in line with the bottom applying plunger.

The bottom blank is fed from the bottom of the stack by a bottom blank picker 196 traveling in guideways 198, actuation being had from a floating link 200 carried by the pin 202 and a link 204 pivoted to a stationary pin 206, an intermittent oscillation being imparted to the floating link by a thrust link 208 operated from an eccentric crank arm 210 pinioned for drive from an intermittently unidirectionally rotated shaft 212 which is given a ninety degree movement for each body blank and bottom blank inserted. Therefore, a quarter turn of shaft 212 causes the juxtapositioning of the bottom blank to the plunger 194 and the upper (bottom) end of the body member 2 in its position *d* as shown in Figures II and VII, and returns bottom picker 196 fully to the right in Figure VI where its motion is arrested while the bottom has glue applied thereto and the initial bonding of the body and bottom blank is effected.

Beneath the position *j* assumed by the as yet undeformed bottom as illustrated in Figure VII, there is positioned a glue pot 214 having four glue applicator rollers 216 arranged exteriorly of the pot with their axis in a square and their inner cylindrical elements forming a closed square of a size corresponding to the dimensions of the bottom area 28 of the bottom blank 26. Feed rollers 218 rotate in the liquid glue 220 and carry the same to rollers 216.

The rollers are preferably power driven directly from main drive shaft to insure uniform feed of glue to the tabs and to this end one set of rollers 218 may be bevel-gearred together and driven by flexible cable from the continuously driven main drive shaft 118, the rollers 216 being preferably driven so that their inner peripheries move upwardly as a result of frictional contact with rollers 218.

The square formed by the sides of the rollers 216 is aligned to coincide axially and angularly with the adjacent end of the body blank in the position *d*.

The body and bottom blanks having taken positions *d* and *j* respectively, they are concurrently moved toward each other, the body 2 being pushed upwardly by a plunger head 222 75

actuated by cam and follower assembly 224 driven by the main drive shaft 118, and the upper edges abutting the ledge 226 surrounding the terminal ends of the wire guide strips 228. Meanwhile the bottom applicator plunger 194 is moved downwardly engaging the bottom blank over the area 28 and forcing it from slots 192 and onto rollers 216 whereon the tabs 38 are arrested and the main portion continues downwardly causing the tabs to be bent along the score line 38 to a position at right angles to bottom portion 28 and to wipe a film of paste onto the lower surface of the tabs after which the plunger 194 forces the bottom into the end of the body 2, as shown at *k* in Figure VIII.

A tight fit of the portion 28 within the surrounding portion of the body 2 is desirable and therefore the plunger 194 is of dimensions such that its edges overlie the score lines 38 of the bottom, so that, as the plunger passes the rollers 216, the tabs are broken back at right angles to the portion 28 and a definite crease is effected along the score line.

Because the tabs snugly engage the sides of the plunger as the position *k* is attained, the return movement of the plunger toward its upper position tends to drag the bottom away from the body. In order to prevent such removal, a separating head 228 is provided which separates the plunger 194 from the bottom after the bottom has reached its applied position as shown in Figure VIII in dotted outline of the separating head.

The construction of the mechanism for operating the applying and separating heads will now be described. Referring to Figures VIII and IX, the head 194 is carried by a vertically reciprocative plunger 230 sliding in bushings 232 and 234 supported on the auxiliary frame plate 236 by a cylindrical housing 238 and said frame plate respectively, all as shown.

Plunger 230 is given an intermittent reciprocative motion by a telescopic cam arm 240 sliding in the open end 244 of the cam crank arm 242. Cam-crank arm 242 is rotatively journaled on the gyratory pin 246 which is fixedly secured to an intermittently unidirectionally driven shaft 248 which likewise finds bearing support 250 on plate 236. Shaft 248 is given a complete rotation during the period of rest of shaft 212, Figure VI, and plunger 194 makes a complete cycle of movement during such period, through action of pinion 252 driven from gear 254 carried on shaft 256 which is sleeved inside hollow shaft 258, Figure I, which is driven from an intermittently actuated and locked helical pinion 260 from a helical gear sector 262 and locking sector 264 driven by shaft 118, whereby gear 252 is given one complete rotation at uniform speed by sector 262 and then positively stopped by the zero pitch sector key 264 entering a longitudinal keyway on the pinion 260.

Head 194 is therefore given a simple harmonic motion by its drive mechanism and is positively locked in inactive position.

It is apparent therefore, that the head 194 moves into position *k* with a diminishing velocity and negative acceleration whereby the application of the bottom to the body is effected with a minimum of impact to the body and yet the approach of the bottom to the body is rapidly achieved.

The control and actuation of the separating head 228 is such that it moves with the head 194 until the bottom is placed in position *k*

whereupon it stops in holding engagement with the upper surface of the portion 28 for an interval of time permitting the head 194 to clear the tabs 30 whereupon the separating head 228 is released and brought back against the head in order to clear the way for juxtapositioning the next bottom blank.

Separating head 228 is fixed to the lower end of shaft 266 which is journaled in head 194 and the arms of a bracket 268 carried on the upper end of shaft 230 for reciprocative movement longitudinally of plunger 230. Pivotedly carried on the cylindrical yoke of bracket 268 is a cam controlled latch arm 270 biased into holding relation with a collar 280 on shaft 266 by a spring 272 carried on the platform arm 274 of bracket 268.

A compression spring 276, surrounding shaft 266 between collar 280 and arm 278 of the bracket, biases the shaft and separator head in extending relation to the applicator head 194. The permitted relative movement is determined by the thickness of the latch 270, or the distance of its upper surface from the surface of the platform 274.

Latch 270 is moved against the tension of its spring to release shaft 266 to remain in the dotted line position of Figure VIII by a stationary cam 282 placed in the path of the latch arm to move the same out of the path of collar 280 at the instant head 194 has placed the bottom in position *k*. Thereupon the spring 276, which is of comparatively low compressive effect, simply holds the stripper head 228 in the dotted line position.

When the head has returned upwardly a distance equal to the thickness of latch 270, platform 274 engages collar 280 to cause shaft 266 and stripper head 228 to travel as a unit upwardly whereby to clear the container unit at the earliest possible moment to permit it to be moved laterally if desired. The head 194 is preferably beveled back from the lower edge to reduce friction on the tabs (not shown).

At this stage of movement of the plunger 230, the head 228 is still held in extended relation to head 194 by spring 276, and collar 280 holds the latch arm 270 in inactive position.

In order to cause the stripper head to resume its full line position of Figure VIII, that is, in substantially flush relationship with head 194, a reset mechanism is provided comprising a trunnion support 284 carried on plunger 230 carrying a pivotal lever 286 having pin and slot connection with shaft 266 whereby movement of said lever causes longitudinal movement of shaft 266.

Arranged in the path of movement of the free end of the lever 286, adjacent the upper end of said path, is a stationary stop or cam 288. Upon engagement of said stop by said lever, the latter is rotated counterclockwise about its fulcrum and causes the shaft 266 to move more rapidly in the upward direction than plunger 230 whereby spring 276 is compressed and latch 270 is released to latching position under collar 280 as shown.

The hollow support 238 is slotted as at 290 and 292 for operation of the plunger and stripper control as is apparent from the drawing.

If desired, the head 228 may be nested into the head 294 to effect a perfectly flat plunger surface, but, since the head 228 may be of thin metal this refinement is unnecessary where small forces are involved.

Referring now to Figure VII it will be noted

that the cam 224 is such that the excursion made by body 2 upwardly is of short duration and occurs just before the bottom blank reaches position *K* of Figure VIII, the excursion being made without loss of time.

In order to insure the proper relative positioning of the bottom in the body blank, the head 194 is provided at its corners with diagonally outward disposed gauge blades 195 which are disposed upwardly from the bottom surface of head 194 a distance equal to the width 32 of the bottom blank, the blade entering between the ends of adjacent tabs 30 and engaging the body blank corners at the end thereof whereby to insure an exact coincidence of the scorelines 38 with the edge of the body blank. If desired, a more positive gauging may be insured by placing the gauging on the stripper head. The gauges and stripper head relocate the bottom with respect to the body end as the head 194 recedes.

The bottom having been applied to the body in the correct position, it adheres thereto by reason of the glue between the opposed areas with the tab portions 37 projecting in the manner shown at 1 in Figure VII in which position these tab portions are bent down in a manner and by the mechanism later to be described.

Positioning and interposition transfer mechanisms

Movable mechanism is provided which assumes successive positions and in each position holds the body or unit for limited movement by another agency to effect further operations on the body or unit, or to finally discharge the unit for transfer to a wax applying unit.

Since it is proposed that bodies 2 of various axial lengths shall be provided with bottoms by one machine it is necessary to make the concerned parts quickly adjustable so that changes may be made for different sizes in a few minutes.

The last operation described above was that of applying the bottom while the body 2 was given an excursion from the position *d* of Figure VIII. The body 2 is held in position *d* in such a manner that it may have a motion of translation along its axis but none of rotation while head 222 gives the translation.

When the body 2 is released to take the position *d* by the cradle arms 124, it has been permitted to nest itself, by utilizing its own tendency to square itself from the diamond shape of Figure IVa, in a set of superposed cradle forming members 300 and 302, Figure I, secured for intermittent step by step rotation, on tubular shaft 304 and to telescoping shaft 306 in shaft 304 respectively, the latter shaft being slidably keyed to said hollow shaft for rotation therewith and extending upwardly into a bushing (not shown) on the upper frame plate 182, where it receives bearing support for free rotation, and support against longitudinal movement, telescoping adjustment being effected by means later to be described.

Shafts 304 and 306 are driven by the helical gear 262 in alternation with the shaft 256 and, when not driven, are locked against rotation by the zero pitch tooth or key. In this case the helical pinion is of such size that a quarter rotation is given shafts 304 and 306 by the sector 262 between successive full rotations of shaft 256. At every quarter of the periphery therefore, the helical pinion 308 is slotted longitudinally to admit the sector 264.

In Figures I and VII the cradle assemblies 300

and 304 are shown only in fragmentary view, the detail being exhibited to better advantage in Figures X and XI. It will be noted that Figure XI overlies Figure X so that the members 300 and 302 with their respective elements may more readily be understood and visualized. In order to incorporate other related structure the lower figure is rotated through about 65 degrees with respect to the mechanism of the upper.

Members 300 and 302 each carry four nesting mechanisms 310 and 312 which are paired in superposed nesting sets located in space quadrature about the central axis of rotation 306.

As shown in Figure XI the lower nesting sets furnish radially flared recesses 314 defined by bounding elements 316 and 318 forming part of the lower cradle member and, preferably, having upwardly disposed inclined wall forming portions 320 furnishing a support tending to permit the body 2 to square itself in the nest. Pairs of resilient arms 322 and 324 are secured to the bounding elements and provide notches 326 and 328 which are positionable so that when the squared body blank is placed therein, the section of the blank will be square as shown at n, the resilient arms resiliently support the body blank or unit in a manner to permit vertical upward movement as heretofore described.

In the position o, Figure XI, the section of the body blank is shown as over-expanded, or reversely partially collapsed which is the position to which it has been constrained prior to release into position d, Figure II. It will now be readily appreciated that, upon release of the cradle arms 124, or 145, Figure XXXV, the body member itself expands until its corners engage into the notches 328 and 326 which hold the carton perfectly square in such position. The flared recesses are such as to permit entry of the leading corner of the container, as shown at 330.

The upper end of the body blank is received in the position o and expands to the position indicated in the flared notch recess 332 forming the upper nesting element of the set.

Together, these nesting elements form a means of fixing the position of the body 2 in alignment with the bottom applicator and against rotation about its own axis. When the pusher 222 rises against the lower end of the blank the latter, being maintained square, sits squarely on the pusher surface, and is forced axially upwardly. As the pusher moves downwardly the spring 276 impels the body 2 downwardly into the position d to clear the same from the plate 182.

After resuming the position d with the bottom attached, the unit is carried clockwise to the position n where it is stopped for an interval during which the next succeeding body is inserted at o, after which the unit is carried to the position p, Figures VII, X, and XI. There it comes to rest in its rotational movement, and is acted upon to bend the tabs 37 over and outwardly and downwardly as shown in Figure XIIa.

Secured to the upper surface of frame plate 182, around an opening 334 therein, is a frame member 340 providing bearing support for four pivotally mounted tab bending tongues 336 carried on shafts 338. Shafts 338 are driven by mutually interconnecting bevel gears 342, Figure V, and by a shaft extension 344 given angular oscillation by a cam arm 346 and a cam 348 driven from shaft 256, Figure VI.

While at the position p the body is given an upward excursion by a pusher 350 also driven by a cam from shaft 118. As the tab portions 37

move upwardly the breaker arms 338 come down on the inside and, moving outwardly and downwardly past the adjacent edge of the body 2, bend the tab portion downwardly to a position at an acute angle to the side of the body, but short of actual contact. In order to positively retain the shape of the remainder of the bottom while the bending is accomplished, both the interior and the exterior of the container is rigidly held in position.

Carried by the breaker arms 338 are lip members 352 which move in behind lips 336 and engage against the inner sides of tab portions 32. Individual leaf springs 354 serve to hold the central portion 28 of the bottom down.

A second and more satisfactory mechanism for retaining the interior form of the bottom while bending the tabs down is shown in Figure XII wherein a plunger head 356 shaped to snugly fit within the bottom recess carries stripper leaf springs 358 and is driven into the recess as the breakers 336 descend. The head is carried by a plunger 360 working in a slideway 362 and is resiliently driven by a pair of springs 364 carried on the breaker arms. By this construction the form is fixed before the portions 37 are engaged by elements 336. The leaf springs insure release of the unit as pusher 350 is retracted downwardly.

The exterior form of the container is fixed partially by the member 302 along two adjacent sides. The remaining sides are briefly engaged by a pair of arms 364 pivoted to the frame as at 366 and actuated by the cam 368 to engage the said remaining sides, and to a clearing position such as to permit free movement of the body 2 into position p. Cam 368 is driven upwardly and downwardly by a pin 370 carried on shaft 338 and passing through a suitable opening in the cam shaft 372. Upon retraction of breakers 336 to the position of Figure VII, the unit is ready for translation to a heat treating mechanism where the portions 32 and 37 are subjected to compression and heat to integrate the same with the embraced edge of the body 2.

The preferred structure for breaking the lips 37 over is shown in Figure XIIa to comprise a square plate 339 carried by a vertically reciprocative plunger 341 sliding in a guideway 343 and having a stop pin 345 for abutment with a stop 347 to exactly terminate the downward motion of the plate so that its forming portion 349 stops in a fixed position with the edges of the body seated against the beveled edge of said forming portion.

Pivotedly carried by the plate 339 are four breaker leaves 351 (two are not shown in order to retain clarity) actuated from their spring biased full line position to their dotted line position by articulated linkages 353, 355, and 357 under control of the crank 359 secured to shafts 338. In operation from the position shown, the arms 359 move downwardly, the various elements below links 357 traveling as a unit, pin 345 is arrested at stop 347 whereupon the plate 339 also stops with its forming portion 349 inside the bottom. At this stoppage, continued movement of links 357 causes plate 355 to slide on plunger 341, compressing spring 361 and causing breaker leaves 351 to rotate to the dotted line position to break the portions 37 over. Stops 363 are provided to exactly limit the rotation of the breaker leaves. After this breakage, the breaker head is withdrawn in reverse order.

Heat and pressure applying mechanism

Referring to Figures I, XIV, and XV to XVIII, the heat and pressure applying mechanism comprises a stationary frame 400 centrally through a bushing 402 of which is fixedly secured a vertical tubular column 404 having fixed against rotation in the upper end thereof an internally threaded nut 406 threaded for rotation through which is a supporting column shaft 408 which is provided with a keyway 410 at its lower end for slideable drive connection with a sprocket hub 412 mounted between thrust plates 414 and 416 of a U-shaped bracket 418 rigidly secured to bushing 404 and providing line support for the shaft 408.

By rotating sprocket hub 412 as by sprocket chain 420, suitable gearing, and hand wheel 422, shaft 408 may be displaced vertically carrying therewith the heat and pressure applying mechanism, the latter being supported on shaft 408 for free rotation with respect thereto, by a suitable thrust roller bearing 424. A cap plate 426 rests upon bearing 424, being centered with respect thereto by an end pin 428 forming part of shaft 408. Depending from cap 426 is a tubular suspension sleeve 430 suitably secured to which is a circular turret 432 depending from the peripheral area of which is a circular arrangement of heat and pressure applying heads 434 into which the bottom ends of successively assembled units are thrust by continuously juxtaposed pads 436 carried on plungers 438 sliding in bushings 440 carried by turntable 442 carried for rotary support around column 404 on thrust bearing 444 and fixedly secured in driving relation to turret drive sleeve 446 which telescopes over tube 404 for line support thereby and rotation therearound and which telescopes within turret suspension sleeve 430 and is provided with a vertical keyway 448 which receives key 450 fixedly mounted through turret hub 452 and suspension sleeve 430 whereby rotation of turntable 442 through the agency of ring gear 454 and suitable gearing from continuously driven shaft 118 causes torque transmission from turntable to turret drive sleeve 446 through key 450 to turret 432, irrespective of the vertical position of key 450 as determined by the position in nut 406 of shaft 408.

Carried on and fixed to cap 426 is an electrical insulator ring 456 embedded in which is a pair of concentric sliprings 460 from which are tapped terminal busses 458, the latter being therefore fixed in relation to the heads 434 to the heating elements of which current conductors may therefore be directly led by suitable insulating cable.

Fixedly secured to the vertically adjustable but otherwise stationary plate 182, by means of a hollow bracket 462, Figure XIV, is a brush carrier hood 464 supporting therewithin in electrically insulating manner, a pair of brushes 466 for engagement with slip rings 460. When shaft 408 is rotated to give vertical displacement to the turret, hood 464 is moved in the same direction and by the same amount by reason of the concurrent vertical adjustment of plate 182.

The power leads may be passed along or within bracket 462 and a second set of straight line electrical brush and bus connectors arranged on plate 182 and a stationary support respectively, so as to completely insulate flexible connections.

It will be observed that by this construction the turret head may be adjusted while the machine is running from shaft 118 without inter-

ferring with the continuous application of heat to the heads 434.

Considering now the Figures XV to XVIII in association with the Figures I and XIV, each of the heat and pressure applying heads 434 comprises a massive heat storage body 468 provided with a neck 470 for securement by means of cap nut 472 to turret 432 as shown. Arranged on the lower flat surface of the head is a shaping and heat applying anvil 474 of a conformation to tightly occupy the bottom recess of the container unit and to have the adjacent tab areas in contact therewith, this anvil being substantially frusto-pyramidal in conformation.

15 Pivottally mounted on the side surfaces of the body 468 between ears 476 on shaft 478 are pressure applying jaws 480 biased to inactive position from a pressure applying position adjacent side surfaces 482 of the anvil by a body seated spring 20 484. The pressure face 486 of jaw 480 is moved toward the anvil through actuation of the tail piece 488, in timed relation later explained, by a cam pin 490 sliding in pin-way 492 and thrusting upon adjustable screw 494, said cam pin having an angular cam surface 496 for actuation by one angular surface of the frusto-pyramidal multiple cam body 498 formed on cylindrical plunger 500 vertically reciprocatively mounted in the central cylindrical bore 502. Integral with 25 the plunger and cam body is a gear rack formation 504, and passing into the diagonal pinion shaft bore 506 in said body in a direction at right angles to the bore 502, is a cam operated rock shaft 508 provided with a pinion 510 for engaging said rack formation 504. Cams 496 and 498 will be observed to be self locking since the squared end of the cam 496 at 512 rides up on the cylindrical surface of the plunger 500.

Received in a bore 514 in the body 468, is an electrical heating unit which is preferably connected electrically to terminals 468 through a suitable temperature regulating thermostatic switch responsive to the temperature of the head to control the same, in a manner known to the heating art.

40 The heads 434 are secured to the turret 432 in such manner that their diagonal vertical sections lie in a radical plane from the turret axis and so that the cam shafts 508 extend nearly 45 radially.

50 Fixedly secured to cam shafts 508 are the cam follower rocker arms 518 provided with cam follower pins 520 and 522 the former of which engages a relatively fixed cam 524, Figure V, on the vertically adjustable plate 182, to cause opening of the jaws 480 and release of the processed unit, and permit ejection of the unit downwardly by leaf spring 526, which, during the heat and pressure period, has been flattened against 474 by 55 the bottom 28. The forward spring has a slightly greater downward displacement than the rearward in order to deflect the lower end to certainly clear the member 680. By this construction, any tendency to integrate the container material with the anvil is overcome.

60 Cam pin 420 is operated upon by a second relatively stationary cam 530, likewise mounted on said plate 182 to cause closing of said jaws in timed relation to other operating mechanisms as hereinafter set forth.

Transfer from cradle mechanism to integrator

65 Referring now again to Figures X and XI it will be observed that the flared notches of the cradle members 300 and 302 are formed partially

by the banding members 318 and 608 which are pivotally mounted on said cradle members by pins 602.

The arms 318 are biased to normal nest forming position in which the associated structure grips the container body 2 in nested relation by springs 604 anchored on said cradle members and connected to pins 606 which conveniently extend through and beneath the member 300 by way of arcuate slots 608 formed in the plate 300 and forming limiting stops for swinging of said arm 318 about the pivot 602 by reason of the spring 604 and a cam 610 lying beneath the plate 300 and fixedly mounted on the top of plate 174 and having a contour lying in the path of pin 606 substantially as shown in Figure XI whereby the arm 318 is caused to move to an open position, as shown in dotted lines, to release the lower end of the unit body for engagement by a second transfer structure presently to be described.

As the pins 606 follow the cam surface 610s the pin is caused to engage a follower arm 612 of a crank couple 614 lying over the then position of the notch and just inside the corner of the unit body, to give as light clockwise rotation to said couple to cause ejection of this lower end and also to square the lower end into the arms of the gripping transfer wheel. A suitably anchored spring 620 returns the ejector couple as the pin 606 clears the same.

The arms 600 on the cradle member 302 are normally biased to form the nest for the upper portion of the body 2 by springs 622 against stops 624 and these arms are opened rearwardly by pins 626 engaging a stationary cam 630 overlying the plate 302 and fixed to the upper plate 182 in the position indicated in dotted lines whereby to cause such opening simultaneously with the opening of arms 318 whereby to release the upper portion of the body to the guide rail 632 and the transfer star-wheel pusher 634. Suitable tongues 636 are provided on the members 302 and 600 to hold the upper portion of the body member in the notches.

As the lower end of the unit is released at the position *t* it is received in the gripping jaws 638 and 640, six sets of which are equally spaced on the gripping transfer mechanism 642. Jaws 640 are controlled by cam 644 fixed to plate 174 beneath member 642 and are held in the inactive clearing position, as illustrated for arm 640a, until the position *t* is cleared by said cam and springs 646, two only of which have been illustrated. Spring anchor pins 648 extend downwardly through arcuate slots 650 in member 642 to engage and follow the contour of cam 644.

After clearing the position *t* and after jaw 638 has engaged the trailing corner of the lower end of the unit as shown, the arm 616 engages the corner 652 of the unit and thereupon the arm-jaw 640 grips the leading corner and holds the lower end square. By this construction the unit is bodily carried with the lower end free from contact with the surface of plate 174. The fixed jaws 638 are arcuately recessed as at 654 for clearance of the same by the corner 656 as the two travel toward position *t*. It will be observed that, since there is a larger number of sets of gripper jaws than nesting sets, jaws 636 move from station to station at a lower velocity than does the container unit whereby the advance to position *t* of the unit is slightly ahead of the jaw 638 and yet the latter comes into position directly behind the unit.

The sets of jaws are arrested to permit the

transfer at *t*. The arrest of the nesting members 318 and 316 at *t* simply positions the unit at this point in a stationary position. After such arrest pin 606 lies in contact with cam surface 610s. The shaft 306, having been arrested for the cycle permitting operations at positions *o* and *p*, rotates another quarter turn during the immediate forepart of which movement, member 318 is sharply retracted to the dotted line position 318'. The plate 300 is recessed to an arcuate limit 301 to clear the released unit. The trailing jaw 638 is in engaging relation to the trailing corner of the unit at the time of release by member 318.

15 The upper ends of the units are simply pushed around star member 634, therebetween and the guide rail 632, there being six arms to this star wheel of such conformation as to maintain the diagonal planes of the container unit radial. 20 The container unit, as it leaves the position *p* of Figure X, has its bottom portion edges flared outwardly and downwardly from which position the portions 37 tend to return to an erect position. Such tendency is overcome and these portions held against movement beyond a horizontal plane by an end confining guide plate, Figures I, V, VII, and XIV, having an inclined portion 662 adjacent the bending unit to effect downward deflection of the portions 37 should the tendency to return upwardly after bending be sufficiently pronounced. As observed from Figure V, the plate 660 partakes of the S shape and is supported by brackets 664 in common with the guide-rail 632 outside the path of movement of 25 the movable elements.

30 The action of the arms 600 at the position *t* is similar to that of the members 318, and the pushing sides of arms 666 of star 634 immediately arcuately recessed at 668 as are jaws 638. Arms 666 are partially comprised of pawl-like members 670 pivotally mounted as 672 and held against stops 674 by springs 676, whereby said pawl-like members may move forwardly, counterclockwise about 672 when engaged from 35 the rear by a passing carton after release of such carton from the succeeding arm to the heat and pressure applying head.

40 Assemblies 642 and 634, assisted by the guide members, convey the container unit in erect position to a position wherein its diagonal plane of symmetry occupies the common plane of the shaft axis 678 and 408, Figure XIV, to the position *u*, Figure V, coming in slightly behind the centering guide 680 above the surface of the pusher plate 436, the latter being at this time in depressed position. The upper portion of the unit's leading corner comes in slightly behind the rigid guide and positioning arm 682 fixedly carried by bracket 684 on turret 432.

45 60 The right angular notches of guides 680 and 682 are positioned to align the bottom edges of the unit for insertion between the faces 482 and 486 of the anvil 474 and clamping jaws 486.

65 As the unit takes the position *u* the gripping jaw 640 moves to the position 640, Figure XI, and immediately thereafter the container unit is forced against the guides 680 and 682 by the cam controlled aligning arm 686 pivotally mounted on bracket tail-piece 688 by a pin 690 and biased to aligning position by a spring 692. The positions of the arms 686 are determined in one limit, the aligning position, by stops 694 engageable with the members 688, and in the other limit by a stationary cam 695 mounted on guide 70 75 75

members 632 and 696 cooperative with which cam are the follower rollers 698.

Prior to reaching the position corresponding to closure upon the container unit at position *u* the arms are held expanded as shown in Figure V and upon release at the dwell 700, shift the unit against the guides 680 and 682 for exact alignment with the head 434, as illustrated in Figures X and XI.

At this time, Figures V and XV, the pressure jaws 480 are in open position, having been actuated to this position by the cam 524, and the plunger 438 is depressed. Immediately upon achieving alignment against the guides 680 and 682, roller 702, Figure XIV, moves upwardly on cam 704 causing the elevation of the body 2 and insertion of the bottom end edges thereof upwardly into the rectangular channel around anvil 474 causing collapse of spring portions 526. The full insertion is completed prior to arrival of pin 520 to engage cam 530, whereupon the jaws 480 move inward to compress the portions 32 and 37 against the embraced end areas of the container body 2. A suitable degree of heat and pressure serve to seal the parts together.

It will be noted that the plate 660 is notched at the position *u* in such fashion as to cause the guidance of the units until they directly underly the heater heads whereby proper alignment of the free tab edges is assured.

After the clamping action above described, plunger 438 is retracted downwardly by cam 706 and the unit remains suspended in process of integration for a definite period of time as determined by the rate of movement in rotation of the turntable 442, and the fact that the process is carried on until the container is released and discharged at a point adjacent the entry point as illustrated in Figure V.

As the unit reaches the point W cam 525 engages arm 522 to cause release of jaws 480 whereupon springs 526 and 528 force the container downwardly onto the depressed plate 436*w*, the arms 682 and 686 remaining in aligning position until this release has been effected and the container rests firmly and squarely on the said plate. Immediately this state has been reached roller 698 engages cam 694 to release the container for lateral movement of the plate.

At this position guide 696, placed above the path of member 680, deflects the container radially outward into the path of a tri-pointed, intermittently actuated, pusher assembly 708 which is timed to enter behind the container. This assembly comprises the upper tri-pointed pusher 712 fixed to the splined shaft 714 rotatively secured in the plate 182 and slidably splined in the hollow shaft 716 to which is fixedly secured the lower pusher member 712 and which shafts are rotated by suitably related sprocket gearing 718 and 720 in common drive relation to the drives for shafts 306 and 678.

The pusher assembly moves the unit to a position for removal from the integrating machine by a conveyor mechanism illustrated in Figure XIX. At a position V, Figure XX, corresponding to a point of pause of the pusher 708 the frame plates 174 and 182 are slotted as at 722 for the passage therethrough in an upward direction, of the lateral arms 724 of a conveyor and erecting wheel 726 mounted for rotation in a vertical plane and traveling within a generally arcuate passageway 728, formed by the upper and lower guide strips 730 and 732, and terminating in a generally vertical delivery chamber 734 overlying

the receiving end of a chain conveyor 736. A port 738 is provided to permit the arms 724 to pass out of the passageway, which port is normally closed by a spring leaf 740 which provides for normal continuity of the interior guideway surface provided by strip 730.

The arms 724 are provided with clockwise directed prongs 742 of a size to fit within the open end of the container and positioned to come into that end of the container after it is positioned in the position V whereupon the container is bodily moved upwardly and arcuately through passage 728 with its large closed bottom end foremost with the result that the container is changed from up side down to erect position and placed on the conveyor 736 for carriage to the wlexer.

The wheel 736 is driven from the shaft 118 from a sprocket 744 and suitable chain and sprocket not shown, in a manner to cause the passage of an arm 722 from beneath to above the pusher 708 while the pusher remains at position V, and so that the pusher may move for the next step prior to entry of the succeeding arm 722.

Adjustment for containers of different lengths

The invention contemplates fabrication of containers of different capacity and to that end it is desirable to provide a single machine which will make containers of various capacities. This invention employs a correlated series of containers having their end areas of substantially the same dimensions whereby the various instrumentalities used in the machine need only be shifted toward and from each other in order to integrate the body and bottom blanks of varied capacity containers. The end edges of the quart and pint container bodies are substantially the same and the bottom blanks for these containers are substantially the same size so that they may be used for both quart and pint sizes, for example. Only the body blank varies in size for different capacities.

Accordingly, the only factors for which the integrating machine heretofore partially described, need be modified in order to accomplish fabrication of containers of various capacities are those dependent on the size and shape of the body blank.

The length is taken care of in the body magazine 102 by means already described, whereby member 178 is movable right and left, Figure II. The cradle brackets 134 are slidable on rods 138. The Y-like cradle arms 124 are adjustable for angularity about the axis of screw 130. The lower termini of cams 160 are adjustable inwardly and outwardly as at 176.

The upper plate 182 and with it the various mechanisms for applying the bottom, breaking the tabs, and cradling the upper end of the unit, including the members 392 and 634 of Figure X, is vertically adjustable in spaced parallelism to the plate 174 and moves simultaneously with the vertical adjustment of the turret 432 when the latter is adjusted by hand wheel 422 and splined shaft 408, Figure XIV.

The adjustment of the upper plate 182 is effected through the threaded supports 746 which form the only means of support for said plate and which are secured for rotation in the plate 182 by any suitable end thrust bearings 748, pass through the plate 174, which gives line support through the medium of bearings 750, and then pass through threaded nuts 752 supported for

trust on the lower fixed plate. The nuts 752 are all driven by a common chain 756 from a sprocket and jack-shaft 758 by chain 420 which is in turn driven by the hand wheel 422 whereby all of the adjustments for length are readily effected.

Sterilization and waxing mechanism

After fabrication of the container as heretofore set forth, it is subjected to sterilizing temperature in a wax bath which, for the purpose among others, of providing a non-absorbent container, forms a coating of wax over the entire inner and outer surface area of the container.

Referring now to Figures XXI to XXV the container is deposited on the conveyor 736 and moves to a position juxtaposed to the wax bath conveyor 760. The containers are permitted to enter in a group of four according to the illustrated modification by cam controlled gates 762 which are actuated to arrest succeeding containers for a period sufficient to permit entry of the preceding group into the individual pockets 764 of the conveyor.

The positioning conveyor 736 is of the type consisting of a series of plates mounted upon a chain and sliding on rails 766 placed laterally of the chain to afford a substantially flat moving surface in the upper reach so that when the containers are arrested by a stop 766 placed in their path, the plates simply slide beneath the containers. Stop 766 is cam actuated to permit a slight overtravel of the containers on the conveyor and, just before they are forced into the pockets, this stop is actuated to position the group in exact alignment with the pockets of the conveyor.

The hot wax is contained in a vat 768 suitably supported in a frame 770 and has supported therein an arcuate guideway 772 suitably perforated to permit free circulation of fluid wax into the upper section of the vat. The conveyor 760 is rotatably mounted on trunnions 774 and comprises a cylindrical drum 776 on which there is mounted channel forming ribs 778 and rearwardly inclined pushers 780 of T shape, the cross of the T being slightly shorter than the interior dimension of the bottom recess of the container unit. The conveyor rotates counterclockwise at a fixed speed, and, as the T member drops below the adjacent surface of the conveyor 736, a synchronized lever 782 pushes the containers from their juxtaposed position and into the pockets formed on the drum.

As the group moves toward the conveyor the units thereof are separated by the countermoving wedges 784, moving to the left in Figures XXI and XXII whereby to cause the bottoms thereof to clear the ribs 778. These wedges also have movement downward between the containers and to these ends are mounted on a bracket 786 pivotally carried on the free end of a stationarily pivoted cam actuated link 788 pivoted at 790 conveniently in common with the pivotally supported lever 782. Levers 782 and 786 are joined by a tension spring 792 the disposition of which is such as to pull lever 786 upwardly and toward the left as shown in the drawings. Carried by the lever 786 is a cam follower 794 and on the link 788 is a second cam follower 796 with which are associated cams 798 and 800 driven by motor 702 acting through drive 704 in synchronism with stop 766 and feeder arm 782 so as to provide the desired leftward and downward motion of the wedges. The motor 702 is also geared to drive the

drum 760 and the cooling conveyor as will be described in the manner indicated by dotted outline for chains and sprockets. A second motor 806 is provided to drive the conveyor 736. Suitable electrical heating units 808 controlled by a temperature-of-bath responsive thermostatic switch are provided. A suitable heat retaining hood, not shown, is preferably provided over the upper parts of the drum.

10 The unit is carried through the bath and is discharged in an erect position by an erector comprising a ledge portion 808 over which the container slides and is fulcrumed with its larger and heavier end foremost between sidewall dividers

15 810 so that gravity tends to erect the container. Ward members 812 combine with the ledge to exactly determine the position of the leading lower edge of the container. For the purpose of different sized containers the erector is replaceable by 20 erectors of different sizes.

After the waxing operation the containers are cooled by a convenient cooling agent such as cold water circulated by a pump 812 circulating water from a cooler 814 to sprinkler heads 816 arranged in spraying relation to the waxed containers as 25 they are carried through the cooling region.

The containers leave the erector through the upwardly convergent opening between wards 812, being slidably supported on rails 818 and driven 30 by pushers 820 carried by chains 822 in a manner to slide on the rails, the chains being driven by sprockets 824 and 826 and driven by motor 802. The rails 818 being stationary provide for a pause in the erector and the pushers 820 cause uniform 35 spacing between successive units.

As the containers move through the spray for cooling they are closed against entry of water therein by means of a series of stoppers 828 which are carried on a chain 830 and which are so

40 shaped and arranged as to enter the open end of the container as it issues from the erector and to effectually seal said end. These plugs or stoppers move forwardly with the pushers 820 in properly spaced relation therewith to accurately enter the 45 containers without rupture or displacement thereof.

The chain is carried on sprockets 832 mounted on shafts on vertically adjustable frame 834 carried by four screw columns 836 set to travel 50 through the nuts 838 and suitable sprocket and bevel gear mechanism 840 for manual adjustment for containers of varying heights. After cooling; the stoppers withdraw from the containers and the containers are pushed over the rotating drum 842 to lean against a fixed rail 844 over a conveyor 846 and to be pushed onto said conveyor by the pusher members 820 whereby a vertical drop to a desired level is simply effected. The drive for the stopper chains and shaft is through 55 a sliding splined shaft 848. A suitable spray collector 850 collects the water for return to the cooler 814.

The conveyor 846 is associated with a suitable filling machine and closure mechanism whereby 60 the fabrication and filling of the containers is all performed in the creamery by a continuus mechanical operation.

Having described the invention and explained the principles of its operation both in the method 65 and a preferred embodiment of apparatus for carrying out that method in accordance with the stature, it will be apparent that other variations of the invention may be resorted to by those skilled in the art for the purpose of accomplishing one or more of the useful results flowing

therefrom without departing from the spirit of the invention. It is therefore to be understood that the disclosed embodiments are illustrative only and the following claims are referred to for a definition of that for which protection is afforded.

That is claimed is:

1. Mechanism for fabricating a frusto-pyramidal container comprising means for receiving the sidewall portion of said container in collapsed state and the end portions in flat state, means for expanding the sidewall portion and positioning the same with its larger end disposed upwardly, a rotary assembly mechanism disposed to receive said sidewall portion, means associated with said rotary mechanism and cooperative therewith to assemble and fit the larger endwall to the upwardly disposed end of said sidewall portion, a rotary integrating device for said assembled portions for receiving said portions in assembled relation with the larger end disposed upwardly, and means for transferring said assembled portions from said rotary mechanism to said integrating device.

2. An integrating head comprising a frusto-pyramidal anvil, means for forcing an assembled container over said anvil, and means adjacent said anvil for forcing the edges of said container against said anvil.

3. A fabricating machine comprising a breaker head, breaker leaves on said head, means for juxtaposing the head within the recessed end of a container, and means for operating said breaker leaves to surround such recessed end in a squeezing manner.

4. A machine for the manufacture of frusto-pyramidal containers comprising; a frame, a hopper on said frame adapted to contain flat frusto-pyramidal body blanks, a hopper on said frame adapted to contain flat end closure blanks for closing an open end of such body blanks, means for expanding said body blanks on said frame, means for deforming said end closure blanks on said frame to fit the body blanks, means for assembling the body and closure blanks, and means on said frame for integrating the assembly.

5. In a machine adapted to assemble end and body blanks to form a container having means for feeding body blanks thereto, said means comprising a hopper having an outlet and means for releasing blanks from said outlet one by one comprising a disc-like member having a flattened periphery rotatably mounted so that either the periphery engages the face of an advancing blank or the flattened periphery escapes the edge of the blank, a stop portion beyond said flattened periphery for stopping said blank therebetween and said disc, and a passage between said stop and said disc whereby said escaped blank is temporarily held therebetween, means for positioning said disc periphery to prevent the advance of succeeding blanks, and means effective thereafter for escaping the temporarily held blank from said stop portion.

6. Means for expanding a flattened body blank comprising a pair of V shaped members for engaging the edges of said blanks, the lines of intersection of sides of said V shaped members being formed by flat surfaces and converging upon a point, and means for adjusting the angle of convergence of said lines of intersection.

7. In a machine of the class described, means for assembling end blanks within the ends of body blanks comprising a plunger adapted to

engage the end blank to force it within the end of the body blank, and means bodily carried by the plunger adapted to hold the end blank in position while the plunger is withdrawn.

8. In a machine of the class described, means for assembling end blanks comprising an anvil of rectangular conformation adapted for insertion within the end of a body blank and within the closure of said end, and breaker arms adapted to fold and press tabs of such closure against the outside of the body blank and against the anvil.

9. In a machine of the class described, means for assembly and gluing of a rectangular ended body blank and a flat closure to form an assembled open-ended closable container, comprising, a frame member having an opening therethrough of rectangular form, glue applicators in alignment with said opening, a rectangular plunger mounted for reciprocation through said opening with its edges in clearing relation only to said applicators and retractable to withdrawn position from said applicators and said opening, means for positioning an end blank in the path of said plunger, means for positioning a body blank in alignment with said opening, and means whereby said plunger forces the blank through the glue applicators to fit the end blank with glue and to the inside of the body blank.

10. Means for forming and integrating an end closure to a rectangular member comprising a rectangular frusto-pyramidal anvil member, a support therefore, means for telescoping a frusto-pyramidal container endwise over said anvil member, and jaw members on said support adapted for clamping an end closure of said container to the body portion thereof against said anvil, and means for withdrawing said telescoping means after such clamping action whereby said container is supported by said forming means.

11. In combination, a first frame member, a second frame member, means supporting said second frame member for adjustment toward and away from said first frame member, means between said members including carton engaging members for engaging the respective ends of a carton body adjacent said members and for moving said carton body along a path between said members, and means on one of said members for assembling a carton end with a carton body held by said engaging means.

12. In combination, a first frame member, a second frame member, means between said members including carton engaging members for engaging the respective ends of a carton body adjacent said members and for moving said carton body along a path between said members, and means on said members for assembling a carton end with a carton body held by said engaging means.

13. In combination, a first frame member, a second frame member, means rotatably mounted between said frame members adapted to carry a carton body in a path between said frame members, means on one of said frame members for assembling a carton end with the carton body during movement between said members comprising a carton end hopper, means for picking carton ends from said hopper and positioning them adjacent the end of a carton body, and means for forcing the carton end into fastened relation with the carton body.

14. In combination, a first frame member, a

second frame member, means rotatably mounted between said frame members adapted to carry a carton body in a path between said frame members, means on one of said frame members for assembling a carton end with the carton body during movement between said members comprising a carton end hopper, means for picking carton ends from said hopper and positioning them adjacent the end of a carton body, means for forcing the carton end into fastened relation with the carton body, and means operative incident to the operation of the forcing means for applying an adhesive to the carton end portions for engagement with the carton body.

15. Means for assembling a carton end to a carton body comprising a frame member providing a carton end pathway therethrough, means providing for the positioning of a carton body with its end juxtaposed with one end of said pathway, means surrounding said pathway for applying a bonding agent to fastenable portions of said carton end in passing therethrough, means for feeding carton ends into said pathway, and means for forcing the carton ends so fed through said path and into fastened relation to the carton body.

16. Means for applying a bonding agent to a rectangular carton end having lateral tabs incident the forcing of such end into a carton body comprising a plurality of rollers adapted to engage the tabs of the flat carton end, and means for forcing the carton end between the rolls, said rolls being arranged to provide an opening therebetween of the rectangular size of the carton end whereby the forcement causes the breaking of the carton end tabs preliminary to their fitting to the carton body, and means for feeding a bonding agent to said rolls for application to the tabs incident the forcement.

17. Means for assembly of a carton end having tabs to an open ended carton body comprising a rectangular arrangement of rollers providing a hollow rectangular carton end path therebetween, means for positioning an open-ended carton body at one end of said path and means for forcing a carton end through said path onto said body.

18. Means for breaking the tabs of a rectangular carton end preparatory to engaging the tabs to a carton body comprising a roller, and means for forcing the carton end tab past said roller so as to break the tab to the desired boundary on said carton end.

19. An arrangement for applying adhesive to carton parts incident the fabrication thereof comprising a vessel having a rectangular opening therethrough defined by inward side walls, pick-up rolls within the vessel parallel to the side walls, and applicator rolls contacting said pick-up rolls and disposed tangentially to the opening defined by said sidewalls.

20. An arrangement as set forth in claim 19, said opening being slightly greater than the area of the carton end defined by the boundaries of the tabs, and means secured to the opening sides of said vessel walls for spacing the adhesive coated tab ends from the walls during passage of the carton end therethrough.

21. An arrangement as set forth in claim 19, said rolls being geared together for equal angular rotation.

22. An arrangement as set forth in claim 17, said rolls being geared together for equal angular rotation.

23. Means for folding the tabs of a carton end and for assembling the carton end into fastened relation with an open ended carton body com-

prising a series of rollers arranged along the edges of the end of the carton body with the body of the roller in each instance disposed laterally of the adjacent edge of the carton, means for positioning a tabbed carton end with the tabs thereof opposed to the rolls, and means for forcing the carton end so that the tabs thereof engage the rolls simultaneously and are uniformly broken back incident the forcing of the carton end toward said carton body.

24. A construction as set forth in claim 23, said last named means including a plunger of the shape of the flat portion of the carton end, and a thin stripper plate on said plunger, and means including a plunger carried by said first plunger and adapted to cause said stripper plate to hold the carton end to the carton body while the first plunger is withdrawn from the carton end and body.

25. A plunger arrangement for inserting a carton end within an open ended carton wherein the carton end is to be stripped from the plunger after engagement of the carton end with the carton comprising a plunger head and rod, a stripper plate mounted on the face of the plunger and adapted to engage a substantial area of the carton end, a plunger secured to said stripper plate and journaled on said first plunger, spring means disposed to extend the stripper plate from said head, means on said first plunger and said second plunger for holding said stripper plate substantially flush with said head, and stationary means adjacent the path of movement of said plungers for releasing and resetting the holding means incident the movement of the head and the stripper.

26. A construction as set forth in claim 25, the arrangement being such that the stripper is released for the stripping function so as to hold the carton end in the assembled position, and including a latch on said first plunger for holding said second plunger and a stationary latch stripping means, and including a lever on said first plunger linked to said second plunger and a stationary lug adapted to engage said lever for resetting the second plunger to the latched position after the stripping operation.

27. A folded carton body shaper and hopper bottom to assembly position transfer device comprising: a rotatable shaft rotatable about a fixed axis with respect to a hopper, a pair of arms secured for rotation with said shaft and thereto for rotation about an axis at right angles to said shaft and extending for rotation about said first axis into a position adjacent said hopper discharge, means carried by said arms for grasping a carton body as it is discharged from said hopper and for commencing the shaping thereof incident to the grasping, and cam means for completing the shaping of the carton body incident the transfer of said body to an assembly position, said cam means operating on said pair of arms.

28. Means for transferring a carton from a hopper comprising an oscillating shaft, a pair of arms carried by said shaft and pivoted thereto on an axis at right angles to the axis of said shaft, means for spreading said arms apart incident their approach to the discharge of a hopper, carton engaging means on said arms adapted to engage the carton folded edges, means operative to position said engaging means for acceptance of the carton incident their approach to the discharge of a hopper and operative to position said engaging means for grasping the carton immediately after acceptance, and means for caus-

ing said arms to come together incident the movement of the carton body away from said hopper.

29. Means for transferring a carton from a hopper comprising an oscillating shaft, a pair of arms carried by said shaft, carton engaging means on said arms adapted to engage the carton folded edges, means operative to position said engaging means for grasping the carton and to position said engaging means for acceptance and release of the carton.

30. A construction as set forth in claim 29, said positioning means comprising a spring operating on said engaging means, a plunger carried by said arm, and means operative on the plunger to cause positioning for acceptance and grasping of the carton.

31. A construction as set forth in claim 29, in combination, a hopper, means for picking cartons from the hopper, and means operative incident to the picking operation for separating the walls of the carton prior to acceptance by said carton engaging means.

32. In combination with a construction as in claim 29, a rotary assembling device having radially disposed carton end receiving notches and engaging means adapted to hold the carton body in shape, and means operating on said arms for shaping the carton.

33. A construction as set forth in claim 29, said engaging means being adjustable radially from said axis and being adapted for adjustment to receive carton bodies of different edge angularity.

34. A construction as set forth in claim 29, said engaging means being adjustable radially from said axis and being adapted for adjustment to receive carton bodies of different edge angularity, and a hopper adapted for adjustment to hold and release the collapsed bodies of frusto-pyramidal containers of different lengths and equal top and bottom areas.

35. A construction as set forth in claim 29, and means for shaping said carton body past proper shape during its transfer.

36. Means for transferring and shaping a carton body, a hopper from which said carton body is received in folded condition, and means for accepting said carton body from said transferring and shaping means in shaped condition, said transferring and shaping means including oscillating arms, and means for causing said arms to move toward and from each other in a direction at right angles to their direction of oscillation, whereby to cause a carton body held therebetween to take shape through compression upon opposite folded edges.

37. Means for discharging flat members from a hopper one by one comprising a pair of members rotatably mounted and having portions thereof disposed for rotation in the path of the discharge of the hopper and engaging the proximate member to be discharged, said members including means to engage the proximate member in one position of their rotation and to release the proximate member in another position of their rotation and including means to stop the released member upon release by the first means, and whereby the first means may be rotated to engage the next proximate member to be discharged prior to the release of the first member by the second means.

38. Means for discharging flat members from a stack or the like comprising a rotatable structure comprising a pair of axially displaced flat

members joined by a shaft portion to separate the flat members by a distance greater than the thickness of the flat members to be discharged, said axially displaced flat members having cut away portions radially displaced about said shaft portion, whereby one of said axially displaced flat members holds the stack while the other is inserted between the first and the second flat members to be discharged.

10 39. In combination with a hopper, means for discharging flattened cartons therefrom one by one, conveyor means disposed endwise of said hopper and reciprocating in extension thereof, means on said conveyor means for accepting cartons discharged from said hopper in flattened condition, and means associated with said conveyor means for shaping said carton acting through said accepting means.

20 40. A construction as set forth in claim 39, said hopper being designed for folded containers of frusto-pyramidal shape, said accepting means being of V shape and disposed so that the discharged folded bodies fall thereinto, and said associated means consisting in part of a cam arrangement whereby the body is released at the end of the conveyance.

25 41. Means for assembling a carton body having an open end with a carton end having tab portions and a body portion so that the body portion of the carton end lies within the end of the carton body and has tab portions lying against the adjacent inside and outside areas of the walls of the carton body comprising a mechanism for folding the carton end around said area while inserting it into the open end of the container and means for thereafter folding the end portions about the end edges of the carton body and against the outside end areas of the wall of the carton body.

30 42. A construction according to claim 41, and means engaging the outside of the carton during the last folding operation.

35 43. Means for assembling a carton body having an open end with a carton end having inside and outside tab portions and a central body portion so that the body portion of the carton end lies within the end of the carton body and has inside tab portions lying against the adjacent inside area of the carton body walls and has outside tab portions lying against or adjacent the outside areas near the end of the carton comprising means for folding the outside tab portions to their positions including an anvil portion adapted for insertion within the end of the carton adjacent the assembled carton end, and folding members pivoted to the anvil member, and means effective only after the insertion of the anvil portion to cause the folding members to turn the outside tab portions.

40 44. Means for assembling a carton body and a carton end having inside and outside tab portions including means for shaping the carton body to receive the carton end, means for shaping the carton end to fit within the end of the carton body, and means for shaping the outside tab portions about the end edges of the carton body.

45 45. Means for carrying a deformable carton having a trapezoidal shape comprising a movable member having means forming a notch side, a member forming a complementary notch side pivoted to the first member, a spring attached to said members tending to form a grasping relation with a carton therein, and cam means for controlling the position of said second member.

50 46. Means as defined in claim 45 and a second

means of a similar character moving adjacent to the path of the first notches, and means for transferring a carton from one carrying means to the other.

47. A construction as set forth in claim 45, a second structure of similar character mounted to move with the first structure whereby a carton is supported therebetween, and means for adjusting the distance between said conveying means whereby to change the length of carton carried thereby.

48. A construction as defined in claim 45 and a second means of a similar character moving into transfer relation to the first means, and means for transferring a carton from one carrying means to the other including means requiring a greater number of notches in the second member than in the first member so that the first member moves stepwise and the second member moves continuously.

49. Means for transferring and integrating a carton body with a carton end assembled thereto to have a recessed end wall and tabs inside and outside the adjacent end areas of the carton comprising a turret member having a series of carton receiving pads reciprocatively mounted thereon, a second turret member mounted in displaced relation to said first turret member for rotation therewith and having a series of heated anvil members paired with the pads, clamp members mounted on said anvil members and means extending from said anvil member for operating the clamp members including cam levers, means for driving said turret members continuously, and means effective at one position of the pads for raising the pads and carried carton so as to insert the anvil member within the assembled end, and means effective immediately thereafter for causing said clamping members to clamp the outside tab portion against the carton body.

50. A construction as called for in claim 49, and means for thereafter withdrawing said pad members whereby the carton is held only by the anvil and clamps.

51. A construction as called for in claim 49, and means for adjusting the distance between the pad members and the anvils whereby to integrate cartons of different lengths.

52. A construction as in claim 49, the second turret member being telescopically related to the shaft of the first turret member and splined thereto, a thrust bearing support for said second turret member, and means for adjusting the position of the bearing support.

53. Means for applying heat and pressure to integrate a carton body with a carton end to have a recessed end wall and adjacent end walls attached to inside and/or outside tabs comprising an anvil member adapted to be inserted within the recessed end, a plurality of clamps surrounding said anvil member for pressing the end portions and tabs together, a support for said anvil and said clamps providing bearings for said

clamps and a heater support for the anvil, a rack reciprocably mounted in said support having a cam portion, means joining said cam portion for actuating said clamps, a pinion and shaft connected to said rack, and means for supporting said assembly to a turret as a unit.

54. Means for applying heat and pressure to integrate a carton body with a carton end to have a recessed end wall and adjacent end walls attached to inside and/or outside tabs comprising an anvil member adapted to be inserted within the recessed end, and a plurality of clamps surrounding said anvil member for pressing the end portions and tabs together, a support for said anvil and said clamps, and means mounted in said support for causing all said clamps to operate simultaneously in response thereto.

55. In a machine for assembling an open ended carton body with an end closure to form a closed ended carton having a recessed end wall and side walls reinforced by inside and outside tab portions of said end closure, means adapted to take carton body portions and end closures from their hoppers in flattened condition and reform said body portions and end closures while moving toward assembly of the end closure to within the end of the carton body portion, means for applying sealing material, and means for folding the outside portions against or adjacent to the outside of the adjacent body wall portions, and means for clamping the tab portions onto the wall portions while applying heat thereto, and means for causing the foregoing operations in serial operation and a plurality of operations to occur concurrently.

56. In a machine for assembling an open ended carton body with an end closure to form a closed ended carton having a recessed end wall and side walls reinforced by inside and outside tab portions of said end closure, means adapted to take carton body portions and end closures in flattened condition and to reform said portions and closures and fasten them together including means for feeding the body portions in step by step fashion to a plurality of stations for the fastening operations, a continuously moving integrating device, and continuously moving means between the integrating device and the step by step feeding means for transferring the assembled and fastened body and closure as a unit to the integrating device.

57. In a machine for assembling and integrating an open ended carton body to an end closure as set forth in claim 56, and means for adjusting the machine whereby carton bodies of different lengths are assembled and integrated in the same machine.

58. In a machine according to claim 56, and means for simultaneously adjusting all parts of the machine whereby carton bodies of different lengths are assembled and integrated in the same machine.

CLAUDE E. POPE.
